APPARATUS FOR THE CONTROL OF
HIGHWAY CROSSING SIGNALSHenry S. Young, Wilkinsburg, Pa., assignor to
The Union Switch & Signal Company, Swiss-
vale, Pa., a corporation of Pennsylvania

Application November 15, 1938, Serial No. 240,521

5 Claims. (Cl. 246—130)

My invention relates to apparatus for the control of highway crossing signals, and has for an object the provision of novel and improved means for governing the operation of a highway crossing signal until a train completely passes the intersection.

Another feature of my invention is the provision of novel and improved means whereby an accidental shunting of the track rails at a highway intersection will not effect the establishment of directional control of the highway crossing signal.

Other objects and advantages of my invention will appear as the specification progresses.

I shall describe one form of apparatus embodying my invention, and shall then point out the novel features thereof in claims.

The accompanying drawing is a diagrammatic view of a preferred form of apparatus embodying my invention.

Referring to the drawing, the reference characters 1 and 1a designate the track rails of a stretch of railway track over which traffic moves in either direction, and which is intersected at grade by a highway H. Located adjacent the intersection is a highway crossing signal S, which may be of any suitable type, but which, as here shown, is an audible signal in the form of an electric bell.

The track rails 1 and 1a are divided by means of the usual insulated rail joints 2 into relatively long sections D—E and F—G separated from each other by a relatively short section E—F. Sections D—E and F—G will usually be of such length suitable to provide an adequate warning period to highway users of the approach of a train to the intersection. Section E—F will usually be of such length as to completely include the intersection.

Section E—F is provided with a track circuit comprising a suitable source of current, such as track battery 3, connected across the track rails at one end of the section, and a track relay designated by the reference character TR, connected across the track rails at the other end. Section D—E is provided with a track circuit which may be traced from one terminal of track battery 3 of section D—E, which is connected across the track rails at one end of the section, through rail 1, wire 4, the winding W1 of an interlocking relay XR to be referred to later, then through two branch paths to wire 5, one branch path of which comprises wire 6, front "flagman" contact 7 of winding W1, and wire 8, the other path of which includes wire 9, front contact 10 of relay

TR, and wire 11, then through wire 5 and rail 1a to the other terminal of battery 3. Section F—G is provided with a track circuit which may be traced from one terminal of track battery 3 of section F—G, through rail 1, wire 12, the winding W2 of relay XR, then through two branch paths to wire 13, one path of which comprises wire 14, front "flagman" contact 15 of winding W2, and wire 16, the other path of which comprises wire 17, front contact 18 of relay TR, and wire 19, then through wire 13 and rail 1a to the other terminal of battery 3.

The interlocking relay XR, previously referred to, may be of any suitable type, such as, for example, the relay covered by United States Letter Patent No. 1,799,629, granted to W. K. Lockhart and T. J. O'Meara on April 7, 1931. This type of relay is well-known and is characterized by the fact that when the left-hand winding W1 is deenergized, the downward movement of the armature associated therewith operates a mechanical locking device which keeps the armature associated with the right-hand winding W2 "locked up" in approximately its mid position, so that the subsequent deenergization of winding W2 while winding W1 is still deenergized cannot close back contact 21. Similarly, if the right-hand winding W2 is first to become deenergized, then back contact 20 is prevented from closing when the left-hand winding W1 becomes deenergized during the interval that winding W2 is still deenergized. Relay XR is also provided with front contacts 7 and 15 associated with windings W1 and W2, respectively, which have what I shall term "flagman" adjustments. That is to say, each "flagman" contact remains closed when its associated armature is in its "locked up" position.

Signal S is provided with a first operating circuit passing from terminal B of a suitable source of current, such as a battery not shown, through back contact 20 of winding W1 or back contact 21 of winding W2, and the operating winding of signal S to terminal C. Signal S is provided with a second operating circuit passing from terminal B through back contact 22 of relay TR and the winding of signal S to terminal C.

When no trains are occupying the control section D—E, E—F, or F—G, the apparatus is in its normal condition. In the normal condition of the apparatus, as shown in the drawing, track relay TR is energized and windings W1 and W2 of relay XR are energized. Signal S is deenergized.

In explaining the operation of the apparatus

embodying my invention, I shall assume that an eastbound train, that is, a train operating from left to right in the drawing, enters track section D—E so that winding W1 releases. When this happens, front contact 7 of winding W1 opens and back contact 20 of winding W2 closes, the closing of this latter contact completing the first circuit for signal S whereby signal S displays its warning exhibit to highway users. When the train enters section E—F, relay TR is shunted and releases to close back contact 22 and to open front contacts 10 and 18. The closing of back contact 22 completes the second energizing circuit for signal S, while the opening of front contact 10 opens the second branch path in the track circuit for section D—E. The opening of front contact 18 of relay TR opens the second branch path in the track circuit for section F—G, but winding W2 is retained energized over its first branch path. Since both the first and second branch paths for the track circuit for section D—E are now open, winding W1 remains released when the train vacates section D—E, until such time as relay TR picks up when the train vacates section E—F. The eastbound train, however, will enter section F—G before it vacates section E—F, so that winding W2 of relay XR is shunted and releases to its "locked up" position prior to relay TR picking up and completing the track circuit for section D—E.

When the train vacates section E—F, relay TR picks up to open back contact 22 and to close front contacts 10 and 18. The closing of front contact 10 completes the track circuit for section D—E with the result that winding W1 picks up to close front contact 7 and to open back contact 20, thereby opening the energizing circuit for signal S. The closing of front contact 18 of relay TR completes the second branch path of the circuit for section F—G with the result that when the train vacates section F—G, winding W2 will pick up to restore the apparatus to its normal condition.

The operation of the apparatus for a westbound train is substantially similar to the operation just described for an eastbound train as will be readily apparent from an inspection of the drawing, and further detailed description is deemed unnecessary.

From the foregoing description of the operation of the apparatus, it is readily apparent that track relay TR provided for the track circuit at the intersection, when released, is effective to prevent the picking up of winding W1 or W2 of relay XR, but is ineffective to release winding W1 or W2. It is readily apparent, therefore, that when one winding of the interlocking relay is released to its full down position to complete the operating circuit for signal S, the track relay TR will prevent that winding from picking up until such time as the interlocking feature of relay XR establishes directional control over the other winding of the relay. That is to say, if winding W1 is released to its full down position by an eastbound train, the presence of the train on section E—F and the resultant releasing of relay TR prevents winding W1 from picking up until after the train enters section F—G, so that winding W2 is released to its "locked up" position prior to winding W1 picking up.

It should be noted that the first branch path for each track circuit for the track sections D—E and F—G includes a front "flagman" contact of its associated winding of the relay XR, whereby the associated winding of the interlock-

ing relay is provided with a stick circuit. It follows that if relay TR is accidentally released due to an accidental shunting of the track rails at the intersection and the track rails of sections D—E and F—G are not shunted, the windings 5 W1 and W2 will remain energized over their respective stick circuits to prevent an establishment of the directional control of signal S. Furthermore, if it is desired to dispense with back contact 22 of relay TR and thus provide only a 10 single operating circuit for signal S which circuit would include back contact 20 or back contact 21 of winding W1 or W2, respectively, it is then apparent that an accidental release of relay TR will not affect the operation of signal S. 15

Although I have herein shown and described only one form of apparatus embodying my invention, it is understood that various changes and modifications may be made therein within the scope of the appended claims without departing from the spirit and scope of my invention. 20

Having thus described my invention, what I claim is:

1. In combination, a stretch of railway track divided into a first section and a third section 25 separated from each other by a second section intersected by a highway, a highway crossing signal located at such intersection, a track relay, a track circuit for said second section including the winding of said track relay, an interlocking relay having a first winding and a second winding, a track circuit for said first section including the first winding of said interlocking relay and a front contact of said track relay, a track circuit for said third section including the sec- 30 ond winding of said interlocking relay and a front contact of said track relay, means governed by a front contact of each of said windings of 35 said interlocking relay for at times providing a shunt path around the front contact of said track relay included in its associated track circuit, whereby said track relay is removed from control of the track circuit of the associated section, and means governed by each of said windings of said interlocking relay for operating 40 45 said signal.

2. In combination, a stretch of railway track divided into a first section and a third section separated from each other by a second section intersected by a highway, a highway crossing 50 signal located at such intersection, a track relay, a track circuit for said second section including the winding of said track relay, an interlocking relay having a first winding and a second winding, a track circuit for said first section includ- 55 ing said first winding of said interlocking relay and a front contact of said track relay, a stick circuit for said first winding of said interlocking relay including a front contact thereof arranged to remove said front contact of said track relay 60 from control of said track circuit for said first section, a track circuit for said third section including said second winding of said interlocking relay and a front contact of said track relay, a stick circuit for said second winding of said 65 interlocking relay including a front contact thereof arranged to remove said second mentioned front contact of said track relay from control of said track circuit for said third section, and means governed by each of said wind- 70 ings of said interlocking relay for operating said signal.

3. In combination, a stretch of railway track divided into two outer sections and an intermediate section, said intermediate section being 75

intersected by a highway and provided with a highway crossing signal located at such intersection, a track relay responsive to traffic conditions in said intermediate section, an interlocking relay having two windings, means for connecting each of said windings of the interlocking relay in a track circuit for a different one of said two outer sections, said means including two alternate paths one of which is a pickup path controlled by said track relay and the other of which is a stick path controlled by the associated winding, and means controlled by each of said windings of the interlocking relay for operating said signal.

4. In combination, a stretch of railway track divided into two outer sections and an intermediate section, said intermediate section being intersected by a highway and provided with a highway crossing signal located at such intersection, a track relay responsive to traffic conditions in said intermediate section, an interlocking relay having two windings one for each of said two outer sections, circuit means for connecting each of said two windings of the interlocking relay in a track circuit for the associated outer section whereby said two windings of the interlocking relay are caused to be responsive to traffic conditions in the associated outer section, means controlled by said track

relay for modifying the control established by traffic conditions in said two outer sections upon said two windings of the interlocking relay whereby said windings are caused to be released only in response to a certain traffic condition in the associated outer section and are caused to become picked up under other traffic conditions in the associated outer section only if said track relay is picked up, and means controlled by each of said windings of the interlocking relay for controlling the operation of said signal.

5. In combination, a stretch of railway track divided into two outer sections and an intermediate section, said intermediate section being intersected by a highway and being provided with a highway crossing signal, a track relay responsive to traffic conditions in said intermediate section, an interlocking relay having two windings one for each of said two outer sections, a stick circuit for each of said two windings controlled by traffic conditions in the associated outer section and completed over a flagman contact of the associated winding, a pick-up circuit for each of said two windings controlled jointly by traffic conditions in the associated outer section and by said track relay, and means controlled by each of said two windings for operating said signal.

HENRY S. YOUNG.
